UNITED STATES PATENT OFFICE.

PAUL M. HASSSLER, OF FAIRFIELD, IOWA, ASSIGNOR TO THE LOUDEN MACHINERY COMPANY, OF FAIRFIELD, IOWA, A CORPORATION OF IOWA.

TRACK FOR OVERHEAD CARRIERS.

1,346,313.

Specification of Letters Patent.

Patented July 13, 1920.

Application filed April 30, 1920. Serial No. 377,844.

To all whom it may concern:

Be it known that I, PAUL M. HASSSLER, a citizen of the United States, residing at Fairfield, in the county of Jefferson and 5 State of Iowa, have invented a new and useful Improvement in Tracks for Overhead Carriers, of which the following is a specification.

My invention relates to tracks for overhead carriers wherein the carriers are to be transferred from one track to another, and it consists of an improvement in the construction and arrangement of said tracks and their connections whereby the transfer 10 can be more easily and safely made, and the carrier may be transferred from one room in a building to another, either above or below it, and also in other features hereinafter described and more definitely set forth in 15 the claims.

In the accompanying drawings forming a part of this specification, Figure 1 is a perspective of a pair of tracks connected to overhead portions of a building and also to 20 overhead portions of a freight elevator arranged to be raised and lowered from one part of the building to another, and embodying the features of my invention. Fig. 2 is the same showing the elevator and adjacent 25 portions of the tracks in different positions. Figs. 3 and 4 are enlarged side elevations, (the latter partly broken away) of portions of the tracks and their connections, which will be hereafter explained. Fig. 5 is a 30 transverse section on line 5—5 of Fig. 4. Fig. 6 is the same on line 6—6, the broken away portion of Fig. 4 being replaced. Fig. 7 is a detail view. Fig. 8 is a section in elevation showing three floors of a building 35 with tracks supported by the two upper floors, and an elevator adapted to pass through the upper floors and the rooms between them, and having a track adapted to be connected to the tracks supported by the 40 upper floors. Fig. 9 is a transverse section on line 9—9 of Fig. 4. Fig. 10 is the same on line 10—10 of Fig. 3.

Referring to the drawings, A represents the cage of a house elevator adapted to pass 45 in the usual manner through an opening in the floors B and B', and having the usual frame work C and C' to protect the opening. As shown in Fig. 1, a pair of overhead tracks D, spaced a distance apart and placed 50 parallel to each other in substantially the

same horizontal alinement, are supported by hangers E secured to overhead portions of the room in which they are installed, F representing a timber of said overhead portion. A corresponding pair of tracks G are supported by hangers H attached to the overhead frame-work I of the elevator cage. On the tracks D, as shown in Fig. 1, a pair of trolleys J are mounted, and are shown connected together by a bar K.

The tracks D and G are connected together by short sections of track-sections L which are hinged to one set of the tracks and when in substantial alinement are connected to the other set so as to form a continuous 60 trackway and permit the trolleys to run from the tracks D to the tracks G, and to be raised, or to be lowered with the elevator, as shown in Fig. 2. Also, to be transferred to corresponding overhead tracks attached to 65 overhead portions of rooms either above or below as shown by D' in Fig. 8, said tracks being connected to the tracks G in a manner similar to their connections with the tracks D.

It is preferable that the connecting sections L be hinged to the tracks D, as shown in the drawings. Any sort of hinge will answer that will properly connect the ends of the tracks D and the track sections L, and 70 will permit the free ends of the latter to be moved upward or downward, as indicated by the dotted lines in Fig. 4, which will be further explained. The preferable form of hinge is shown in Fig. 3. It consists of two 75 pairs of clamping members M and N, hinged together and adapted to clamp between them the adjacent ends of the tracks D and the track sections L, and permit the upward 80 and downward movements of the free ends 85 of the sections L.

It is also preferable that the adjacent ends of the parts D and L be separated to some extent so that the hinge joint may be centrally located. This will insure greater freedom of movement of the sections L. When 90 this is done the clamp members M should be provided with flanges O extended laterally on each side as shown in Fig. 10 to occupy the space between the adjacent ends of the 95 flange members, said flanges being the same width and located in the same plane as the portions of D and L upon which the trolley wheels run, thus forming a continuous trackway.

The connections between the sections L and the tracks G are most plainly shown in Figs. 4, 5 and 6. Clamping members P are applied to the lower portions of the ends of the tracks G, and are extended out beyond said ends to form supports for the adjacent ends of the track sections L, a recess being provided between the extended ends of the members P to receive and hold the inserted end of the section L the lower portion of the extended end of the clamp member P on the near side, as shown in Fig. 4, being broken away. When the elevator is brought into position so that its tracks G will be in horizontal alignment with the tracks D, the sections L are lifted from the vertical position shown in Fig. 2 and are placed in the horizontal connected position shown in Fig. 1, the outer ends of the sections resting in the recesses between the extended ends of the members P.

To hold the sections L in this position while the trolleys are being transferred from the tracks D to G, and vice versa, members Q are applied near the ends of the tracks G,—preferably by clamping on their upper edges as shown in Fig. 9,—and locking dogs R are pivoted between the upper ends of these members. These locking dogs are provided with downwardly projecting points R' which will normally stand over the ends of the sections L and will prevent them from being lifted or otherwise removed from the recesses in the extended ends of the members P. The members Q being narrow and centrally located will leave room for the trolley wheels to run on the edges of the track rail G.

When tracks of the form shown in the drawings are used it is preferable that portions of the upper webs at the ends of the tracks G and sections L be cut away as shown in Fig. 4, so as to let the parts R' come closer to the wheel supporting portions of the trackway. In placing section L in operative position the point R' will be pushed back against the member Q by the descending end of the track section L until it passes under when the overbalancing weight of the opposite end of the dog R will swing the end R' out over the end of the section L.

When the elevator is moved either upward or downward the sections L will be automatically disconnected from the members P and will drop to the vertical position shown in Fig. 2. This is accomplished by the free ends of the sections assuming either the upwardly or downwardly inclined position shown by the dotted lines in Fig. 4, and the consequent drawing away of the free ends of the sections L from the extended ends of the members P. If the elevator is raised the free ends of the sections will be correspondingly raised and will assume the po-

sition shown by the lower dotted lines. If the elevator is lowered the free ends of the sections will be lower and will assume the position shown by the upper dotted lines. It will be understood that the sections L are hinged to the ends of the tracks D, as shown in Fig. 3 and that the end of said section shown by full lines in Fig. 4, is simply laid in the recess in the extended ends of the members P. The dotted lines in Fig. 4 are intended to represent the end of the section slipping out of said recess as the elevator is raised or lowered when it will assume the position shown in Figs. 2 and 3.

To prevent the trolleys from running off the tracks G when the sections L are disconnected, I use a stop device S which is pivoted between the extended ends of the members P in such a manner that when the section L is placed in operative position it will rest on the stop device and will hold it up even with or above the lower edges of the members P, as shown in full lines in Fig. 4. When in this position the trolleys will be free to run over the sections L from the tracks D to G, and vice versa. The lower portion of the extended end of the member P on the near side is broken away to show the stop device S more plainly, but is replaced in the cross-section shown in Fig. 6.

When the sections L are disconnected the inner free end of the stop S will drop down as shown by the dotted lines in Fig. 4, and will come in contact with the portion of the trolley frame J below the track, and will prevent it from running off the open end of the track G. To limit the drop of the stop device it is preferably provided with lugs T which when the stop has dropped to a sufficient extent, will contact with adjacent portions of the members P and will prevent it from dropping further.

If desired a single line of track may be used as shown in Fig. 8 instead of the pairs of tracks shown in Figs. 1 and 2 and this will answer well when single trolleys are used. But with connected trolleys as shown in the drawings, or with carriers having wheels extended some distance apart it is better to use pairs of tracks and to run the trolleys abreast of each other or the carriers sideways instead of endways on the tracks. In this way the carriers or the connected trolleys can be bunched on the tracks G on the elevator and a much larger number of them can be handled at a time than if a single line of track was used and the carriers or connected trolleys were run endwise on the track.

In the drawings the frame member which connects the upper and lower portions of the elevator cage together is represented by U, and braces V to strengthen the frame are also shown. W represents the hoisting cable by which the elevator is raised and

lowered. In Fig. 8, tracks D and D' are shown in the upper and lower rooms adapted to connect with the track G of the elevator on each side, which is simply an extension 5 of the construction shown in Figs. 1 and 2, but does not involve any additional improvement. The hangers E supporting the upper tracks D are shown connected to overhead timbers F' and the hangers H to a portion 10 of the elevator frame I'. The hangers E' supporting the lower tracks D' are connected to timbers F''. The lower floor B'' is preferably provided with a depression or a pit X to receive the floor Y of the elevator when 15 in lowered position.

What I claim is:

1. In tracks for overhead carriers, the combination with an elevator adapted to be raised and lowered through upper and lower 20 rooms of a building, of a track connected to each of the overhead portions of a plurality of said rooms, a corresponding track connected to the overhead portions of the elevator, a trolley adapted to run on said overhead tracks, and means when in horizontal alinement to connect the track in each of the rooms with the track in the elevator, and to form a continuous trackway for the passage 25 of the trolley from the track in a room to the track in the elevator, and vice versa.
2. In tracks for overhead carriers, the combination with an elevator adapted to be raised and lowered through upper and lower rooms of a building, of a track connected to 30 each of the overhead portions of a plurality of said rooms, a corresponding track connected to the overhead portions of the elevator, a trolley adapted to run on said overhead tracks, means when in horizontal alinement to connect the track in each of the rooms with the track in the elevator, and to form a continuous trackway for the passage 35 of the trolley from the track in a room to the track in the elevator, and vice versa, and means to automatically disconnect said 40 tracks.
3. In tracks for overhead carriers, the combination with an elevator adapted to be raised and lowered through upper and lower 45 rooms of a building, of a pair of spaced apart parallel tracks in substantial horizontal alinement, connected to each of the overhead portions of a plurality of said rooms, a pair of corresponding tracks connected to the overhead portions of the elevator, a pair of connected trolleys adapted to run abreast on said overhead tracks, and means to connect the tracks of the rooms with the tracks in the elevator, and to form 50 continuous trackways for the passage of the trolleys from the tracks of a room to the tracks in the elevator, and vice versa.
4. In tracks for overhead carriers, the combination with an elevator adapted to be raised and lowered through upper and lower 55 rooms of a building, of a pair of spaced apart parallel tracks in substantial horizontal alinement connected to each of the overhead portions of a plurality of said rooms, a pair of corresponding tracks connected to the overhead portions of the elevator, a pair of connected trolleys adapted to run abreast on said overhead tracks, and means to connect the tracks of the rooms with the tracks in the elevator, and to form 60 continuous trackways for the passage of the trolleys from the tracks of a room to the tracks in the elevator, and vice versa.
5. In tracks for overhead carriers, the combination with an elevator adapted to be raised and lowered through upper and lower 65 rooms of a building, of a pair of spaced apart parallel tracks in substantial horizontal alinement connected to each of the overhead portions of a plurality of said rooms, a pair of corresponding tracks connected to the overhead portions of the elevator, a pair of connected trolleys adapted to run abreast on said overhead tracks, and means to connect the tracks of the rooms with the tracks in the elevator, and to form continuous trackways for the passage of the trolleys from the tracks of a room to the tracks in the elevator, and vice versa, and means to automatically disconnect said tracks.

rooms of a building, of a pair of spaced apart parallel tracks in substantial horizontal alinement connected to each of the overhead portions of a plurality of said rooms, a pair of corresponding tracks connected to the overhead portions of the elevator, a pair of connected trolleys adapted to run abreast on said overhead tracks, means to connect the tracks of the rooms with the tracks in the elevator, and to form continuous trackways for the passage of the trolleys from the tracks of a room to the tracks in the elevator, and vice versa, and means to automatically disconnect said tracks.

5. In a device of the character described, the combination of an elevator having a frame adapted to be raised and lowered through rooms in a building, a track connected to overhead portions in a plurality 80 of said rooms, a corresponding track connected to overhead portions of the elevator frame, a trolley adapted to run on said tracks and be transferred from one to another, and a track-section hinged to one of the tracks and adapted to be connected to the corresponding track and form a continuous trackway for the passage of the trolley from one track to the other and vice versa.

6. In a device of the character described, the combination of an elevator having a frame adapted to be raised and lowered through rooms in a building, a track connected to overhead portions in a plurality 95 of said rooms, a corresponding track connected to overhead portions of the elevator frame, a trolley adapted to run on said tracks and be transferred from one to another, and a track-section hinged to the end of the track in a room and adapted when in substantial alinement to be connected to the end of the track in the elevator, substantially as and for the purpose set forth.

7. In a device of the character described, the combination of an elevator having a 110 frame adapted to be raised and lowered through rooms in a building, a track connected to overhead portions in a plurality of said rooms, a corresponding track connected to overhead portions of the elevator frame, a trolley adapted to run on said tracks and be transferred from one to another, a short track section, a hinge member secured to the adjacent ends of the track section and the track in the room and means 115 to connect the other end of the track-section to the adjacent end of the track in the elevator, substantially as and for the purpose set forth.

8. In a device of the character described, 125 the combination of an elevator having a frame adapted to be raised and lowered through rooms in a building, a track connected to overhead portions in a plurality of said rooms, a corresponding track con- 130

- 41
- nected to overhead portions of the elevator frame, a trolley adapted to run on said tracks and be transferred from one to another, a short track section, a hinge member secured to adjacent ends of the tracks, having laterally extended portions near its center corresponding with the wheel supporting portions of the tracks, said ends being spaced apart to admit the laterally extended portions of the hinge member, and means to connect the other end of the track section to the adjacent end of the track in the elevator, substantially as and for the purpose set forth.
- 15 9. In a device of the character described, the combination of an elevator having a frame adapted to be raised and lowered through rooms in a building, a track connected to overhead portions in a plurality of said rooms, a corresponding track connected to overhead portions of the elevator frame, a trolley adapted to run on said tracks and be transferred from one to another, a short track section, a hinge member secured to the adjacent ends of the track section and the track in the room, and members applied to the adjacent end of the track in the elevator having extended ends provided with means to receive and support the free end of the track-section.
- 20 10. In a device of the character described, the combination of an elevator having a frame adapted to be raised and lowered through rooms in a building, a track connected to overhead portions in a plurality of said rooms, a corresponding track connected to overhead portions of the elevator frame, a trolley adapted to run on said tracks and be transferred from one to another, a short track section, a hinge member secured to the adjacent ends of the track section and the track in the room, and members applied to the adjacent end of the track in the elevator having extended ends provided with a recess to receive and support the free end of the track-section, an upwardly extended member applied to the elevator track near its end, and a dog pivoted near the upper end of said member and adapted to hold the track section in connected position.
- 25 11. In a device of the character described, the combination of an elevator having a frame adapted to be raised and lowered through rooms in a building, a track connected to overhead portions in a plurality of said rooms, a corresponding track connected to overhead portions of the elevator frame, a trolley adapted to run on said tracks and be transferred from one to another, a short track section, a hinge member secured to the adjacent ends of the track section and the track in the room, and members applied to the adjacent end of the track in the elevator having extended ends provided with a recess to receive and support the free end of the track-section, an upwardly extended member applied to the elevator track near its end, and a dog pivoted near the upper end of said member and provided with a downwardly extended end to hold the track section in the aforesaid recess.
- 30 12. In a device of the character described, the combination of an elevator having a frame adapted to be raised and lowered through rooms in a building, a track connected to overhead portions in a plurality of said rooms, a corresponding track connected to overhead portions of the elevator frame, a trolley adapted to run on said tracks and be transferred from one to another, a short track section, a hinge member secured to the adjacent ends of the track section and the track in the room, and members applied to the adjacent end of the track in the elevator having extended ends provided with a recess to receive and support the free end of the track-section, and a member pivoted in the recess and held even with the lower edge of the extended member by the track section while in the recess to permit the passage of the trolley and one end of said pivoted member to drop below when the track section is removed to come in contact with a portion of the trolley frame and prevent it from running off the track.
- 35 13. In a device of the character described, the combination of an elevator having a frame adapted to be raised and lowered through rooms in a building, a track connected to overhead portions in a plurality of said rooms, a corresponding track connected to overhead portions of the elevator frame, a trolley adapted to run on said tracks and be transferred from one to another, a short track section, a hinge member secured to the adjacent ends of the track section and the track in the room, and members applied to the adjacent end of the track in the elevator having extended ends provided with a recess to receive and support the free end of the track-section, an upwardly extended member applied to the elevator track near its end, and a dog pivoted near the upper end of said member and adapted to hold the track section in connected position.
- 40 14. In a device of the character described, the combination of an elevator having a frame adapted to be raised and lowered through rooms in a building, a track connected to overhead portions in a plurality of said rooms, a corresponding track connected to overhead portions of the elevator frame, a trolley adapted to run on said tracks and be transferred from one to another, a short track section, a hinge member secured to the adjacent ends of the track section and the track in the room, and members applied to the adjacent end of the track in the elevator having extended ends provided with a recess to receive and support the free end of the track-section, and a member pivoted in the recess and held even with the lower edge of the extended member by the track section while in the recess to permit the passage of the trolley and one end of said pivoted member to drop below when the track section is removed to come in contact with a portion of the trolley frame and prevent it from running off the track.
- 45 15. In a device of the character described,

- the combination of an elevator having a frame adapted to be raised and lowered through rooms in a building, a track connected to overhead portions in a plurality 5 of said rooms, a corresponding track connected to overhead portions of the elevator frame, a trolley adapted to run on said tracks and be transferred from one to another, and a track-section hinged to the end of the 10 track in a room and adapted when in substantial alinement to be connected to the end of the track in the elevator, and to automatically disconnect from said track when the elevator is raised or lowered.
- 15 16. In a device of the character described, the combination of an elevator having a frame adapted to be raised and lowered

through rooms in a building, a pair of spaced apart parallel tracks in substantial alinement, connected to overhead portions in a plurality of said rooms, a pair of corresponding tracks connected to overhead portions of the elevator frame, a pair of connected trolleys adapted to run abreast on said tracks and be transferred from one set 20 to the other, and a pair of track sections hinged to one of the sets of tracks and adapted to be connected to the other set and form a continuous track-way for the passage of the trolleys from one to the other and vice 25 versa.

Fairfield, Iowa, April 28th, 1920.

PAUL M. HASSLER.
